UNITED STATES PATENT OFFICE.

ALBERT G. SCHMIDT, OF NEWARK, NEW JERSEY.

PORTABLE STOVE.

SPECIFICATION forming part of Letters Patent No. 499,892, dated June 20, 1893.

Application filed October 14, 1892. Serial No. 448,822. (No model.)

To all whom it may concern:

Be it known that I, ALBERT G. SCHMIDT, a subject of the German Emperor, residing in Newark, county of Essex, and State of New Jersey, have invented certain new and useful Improvements in Portable Stoves; and I do hereby declare the following to be a full, clear, and exact description of the invention, such as will enable others skilled in the art to which it appertains to make and use the same, reference being had to the accompanying drawings, and to letters and figures of reference marked thereon, which form a part of this specification.

The object of my present invention is to provide a portable stove, simple and durable in construction, great in efficiency, and which stove, by means of its peculiar construction can be used for warming or heating one or more apartments at the same time.

The invention consists in the novel and peculiar construction of the stove, and in the combination and arrangement of the various parts thereof, substantially, as will be herein-after more fully described and finally embodied in the clauses of the claim.

Similar letters of reference indicate corresponding parts in each of the several figures.

Figure 1 is a perspective view of the stove. Fig. 2 is a central vertical section through Fig. 1. Fig. 3 is a sectional view on lines *x y* of Fig. 1 and Fig. 4 a sectional view on line *z* of Fig. 2.

In said drawings *b* represents the stove, provided with bottom plate *k* and top plate *i*, securely fastened together by bolts *o* or in any desired manner.

Within the stove is arranged a partition *d*, separating the fire-place and grate *e*, from the fresh air supply chamber 4. The upper portion of said partition is cupola shaped and is provided with a pipe *f*, extending through top plate *i*, as clearly shown in Fig. 2 of the drawings.

Within the cupola shaped portion of the fire-place, but below the tube *f* are arranged two metallic plates *g* and *h*, one a certain distance above and overlapping the other, and are adapted to serve as smoke consumers.

The bottom plate *k* is provided with an air inlet or opening *n*, and the top plate with opening or outlet *m*.

On top of said stove and resting on plate *i* are arranged alternately a series of chambers *w* and *q*, formed by the metallic plates *r* and *s* and the side frames 3 and 5 respectively. The frames 3 are preferably made out of tiles and are secured to the metallic plates by cement or in any desired manner; the frames 5 are made out of metal and are provided with a series of slots; which by the old style of sliding plates can be opened or closed, as will be manifest. This sliding arrangement is not shown in the drawings, and requires no further description, as I have made no claim thereon. Each of the metallic plates *r* and *s* is provided with a centrally located opening and with two openings arranged radially around said central opening, as clearly shown in Fig. 3 of the drawings. In said openings are arranged or inserted tubes or pipes *u* and *t*, connecting the chambers *w* and *q* respectively. The top *c* is also provided with a centrally located opening 6 and with two side openings, the latter ones being connected together by a tube *v*. Said opening 6 may be provided with a damper (not shown in the drawings) or can be connected to a tube, by means of which the heated air is carried into other sections of the building, as will be manifest. The chambers *q* are also provided with division plates 2 (Fig. 3) (arranged substantially in a plane with the division plate *d* of the stove *b*), thus providing two compartments 7 and 8 in each of said chambers. (Fig. 2.)

In operation, the heat and smoke will pass through tube *f* into compartment 7 of the lowest chamber *q* and from there through connecting tubes *t* into the corresponding compartments of the chamber *q* arranged above. Through the connecting tube *v* on top of the stove, and through connecting tubes *t*, the smoke and heat from the fire will enter the various compartments 8 of chambers *q*, and will be finally discharged through tube *p* into the chimney. By this circulation, the air contained in the chambers *w* is thoroughly heated, and can either be let out through the slots in the frames 5 into the room in which the stove is placed, or can—as heretofore stated—be carried into distributing pipes, if desired.

As can be seen from the drawings, the tube *p* before entering the chimney passes through the fresh air supplying chamber 4, whereby

the air passing through said chamber, becomes heated to a certain extent.

I do not intend to limit myself to the construction shown and described, as various alterations can be made without changing the scope of my invention, but

What I claim as new, and desire to secure by Letters Patent, is—

1. In a stove the combination with the fire-place and the fresh air supply chamber, of a plate arranged on top of said fire-place and said air supply chamber, a tube on said fire place and extending through said plate, and two series of chambers arranged alternately on said plate, one of said series being connected with the tube on the fire-place and the other series—with the air supply chamber, all said parts, substantially as described and for the purposes set forth.
2. In a stove, the combination with the fire-place and the fresh air chamber, of two series of chambers arranged alternately above said fire-place, one of said series being connected with the said fire-place, the other series—with the air supply chamber and a tube extending through the air supply chamber and adapted to connect the first series of chambers with the chimney, all said parts, substantially as described and for the purposes set forth.
3. In a stove, the combination with the fire-

place and fresh air supply chamber, of two series of chambers arranged alternately above said fire-place, one of said series being connected with the fire-place, the other—with the air supply chamber, division plates arranged in the first series of chambers and a tube adapted to connect said first series of chambers with the chimneys, all said parts, substantially as described and for the purposes set forth.

4. In a stove, the combination with the fire-place and air supply chamber, of a cupola top arranged on said fire-place, two metallic plates arranged in said cupola top and overlapping each other, two series of chambers arranged alternately above the fire place, one of said series being connected with the cupola top—the other series with the air supply chamber, and a tube extending through the air supply chamber, and adapted to connect the first series of chambers with the chimney, all said parts, substantially as described and for the purposes set forth.

In testimony that I claim the foregoing I have hereunto set my hand this 24th day of September, 1892.

ALBERT G. SCHMIDT.
